UNITED STATES PATENT OFFICE.

FRANK A. PFEIFER AND CHARLES NAAB, OF NEWARK, NEW JERSEY; SAID NAAB AS-SIGNOR TO THOMAS MILLS, OF MAPLEWOOD, NEW JERSEY.

GAME APPARATUS OR AMUSEMENT DEVICE.

Application filed April 1, 1921. Serial No. 457,760.

To all whom it may concern:

Be it known that we, FRANK A. PFEIFER and CHARLES NAAB, citizens of the United States, residing at Newark, in the county of

5 Essex and State of New Jersey, have invented certain new and useful Improvements in Game Apparatus or Amusement Devices; and we do hereby declare the following to be a full, clear, and exact description of the 10 invention, such as will enable others skilled in the art to which it appertains to make and use the same, reference being had to the accompanying drawings, and to characters of reference marked thereon, which form a part 15 of this specification.

This invention has reference, to improvements in amusement devices, and, the present invention relates, more particularly, to a novel and simply-constructed amusement 20 device, representing in miniature a roller-coaster, and which is adapted for use, more especially, as a game-apparatus.

The present invention has for its principal objects to provide a novel and simply 25 constructed amusement device, adapted as a game, the game when played affording both pleasure and amusement to the players.

Other objects of the present invention not at this time more particularly enumerated 30 will be clearly understood from the following detailed description of the present invention.

The invention is clearly illustrated in the accompanying drawings, in which:—

35 Figure 1 is a side elevation of a game-apparatus or amusement-device, showing one embodiment of the principles of the present invention; and Figure 2 is a plan view of the same.

40 Figure 3 is a vertical sectional representation of certain portions of the device, said section being taken on line 3—3 in said Figure 2, and said view being made on a slightly enlarged scale; and Figure 4 is a detail vertical sectional representation, taken transversely on line 4—4 in said Figure 2, said view being made on a still larger scale.

45 Figure 5 is a plan or top view of a magnetic toy life-buoy used with the device; and Figure 6 is a transverse vertical sectional representation of the same, said view showing in elevation, a toy-figure attracted by the magnet of said buoy.

50 Figure 7 is a longitudinal vertical section 55 of a tank adapted to contain water, showing

in connection therewith, the use of said magnetic life-buoy, for lifting or raising a toy-figure above the surface of the water in said tank.

Similar characters of reference are employed in the said above described views, to indicate corresponding parts.

Referring now to the several figures of the drawings, the reference-character 1 indicates a suitably shaped base or table, which is 60 mounted upon a suitably constructed framework 2. As shown more particularly in Figures 1 and 2 of the drawings, two inclines, as 3 and 4, are suitably mounted upon said base or table 1, each incline consisting 65 of the base-piece 5, suitably secured to the table 1 by means of any suitable fastening devices, and the vertical posts 6, the said base-pieces 5 and posts 6 being connected by means of inclined stringer-pieces 7. If desired, standards or supports, as 8, may be disposed between each base-piece 5 and the inclined stringer piece 7 located above the base-piece 5. Each pair of stringer pieces 70 are suitably tied by means of suitably disposed rail-carrying bars or elements 9.

Adjacent to the edge 10 of the said base or table 1, and at one side of the top of the table, is a suitably shaped tank 11, adapted to contain water, and extending beyond the 85 said edge 10 of the said table, and located at the other side of the top of the table is an extension, as 12. Suitably secured to said extension are the end-portions of a pair of carrier-rails or tracks 13, which extend in 90 an upward direction up the incline 3, being suitably secured to the tie-bars or elements 9, the rails or tracks then being curved, as at 14, and descending, as at 15, down the incline 4, being suitably secured to the tie-bars or elements 9 of said plane 4, and terminating, as at 16, directly above the previously mentioned tank 11, as will be seen from an inspection of Figure 2 of the drawings. As shown more particularly in Figure 100 3 of the drawings, the base or table 1 is provided with openings 18 and 19, and located directly beneath the opening 18 is a sprocket-wheel 20, mounted upon a shaft or axle 21, which is rotatably disposed and extends laterally beneath the base or table 1, substantially as indicated in Figure 2 of the drawings. At its one end, the said shaft 21 is provided with a drive-pulley or wheel, as 105 22, or other suitable means for the applica-

110

tion of a motive power, for driving said shaft, as will be evident.

In alignment with said sprocket-wheel 20 is a second sprocket-wheel 23, said sprocket-wheel 23 being mounted upon a shaft 24 which rotates in bearings connected with standards or posts, as 25. Mounted over said sprocket-wheels 20 and 23 is a sprocket or link-chain 26, with a portion of which is 10 suitably connected, in any desired manner, an upwardly extending push-lug or dog 27, the lower portion 28 of which is inserted between the links of the chain 26, substantially as shown in Figure 4 of the drawings, and 15 the lug or dog 27 being maintained in its upright position by means of a bracing member, as 29. The relation of affixing said push-lug or dog 27 to the chain 26 is such that it will travel with the chain over the 20 sprocket-wheel 23, moving in a direction beneath the tie-bars or elements 9, without displacement from the chain, and passing over the sprocket-wheel 20 will again assume its 25 upright relation with the upwardly travelling portion of the chain, as will be understood.

Movably disposed upon the previously mentioned rails or tracks, but being adapted to be lifted therefrom, are the flanged 30 wheels 31 of a toy-car or gondola, as 30, which is formed at its rear end with an extension 32 with which the push-lug or dog 27 is adapted to be brought into operative engagement, as shown in Figures 1 35 and 3 of the drawings, and for the purposes of pushing the car up the incline 3, as will be clearly understood.

Referring now once more to Figure 2 of the drawings, it will be seen, that within the 40 tank 11, there may be disposed a suitably formed current-agitator, 33, which may be made in the form of a paddle-wheel, or otherwise, the said paddle-wheel in this case being mounted upon a shaft 34 which extends through the side of the tank 11, and has a pulley-wheel 35 upon its free endportion. The previously mentioned shaft 21 is also provided with a pulley-wheel 36, a belt 37 passing over said wheel 36 for driving the pulley-wheel 35 and rotating the shaft 34 and paddle-wheel 33. Suitably clamped over the edge of the tank 11, by means of a hook-shaped member 39, is a supporting post 38 which carries a small platform 40, usually surrounded by a railing 41. Mounted upon this platform 40 is a toy-figure 42, usually a doll, to the hands of which may be affixed and passed over one of its shoulders, a flexible connection or cord, 45 as 43, said connection being passed through guiding elements or eyes, as 44, extending from the side of the tank 11, and having its free end-portion 45 attached to a pin 46, connected with the shaft 21, but eccentric 50 with relation to the rotation of said shaft

and whereby the said toy-figure or doll 42 will receive an oscillatory movement, which causes the end-portion 47 of the flexible connection or cord 43 to be alternately raised and lowered, as will be evident. Attached to the said end-portion 47 of the flexible connection or cord is the previously mentioned toy life-buoy, the latter being indicated by the reference-character 48. The said life-buoy, as will be seen from an inspection of Figures 5 and 6 of the drawings, consists essentially of a ring-shaped envelope or body 49 provided with a padding 50. Suitably secured within said envelope 49 is a ring-shape magnet 51, which is cut away, as 52, to provide the usual poles of the magnet, and the marginal edge-portion 53 of said magnet projecting from said envelope and extending into the open portion 54 of the life-buoy, substantially as shown in said Figures 5 and 6, and for the purposes to be presently more fully set forth.

Adapted to be placed within the body of the previously mentioned car 30, are a number of toy-figures or dolls, as 55, the said dolls being hollow and being made of a light material, such as celluloid, so that each doll when placed in water will float. In order that the dolls will float in their upright positions in the body of water, in the manner represented in Figure 7 of the drawings, the lower part of the body of each doll is provided with a weight, as 56, and the upper portion or head of each doll is provided with a small piece of metal 57, usually a piece of wire in the form of a loop, forming part of an ornamental cap-portion 58 of the doll.

Having in the foregoing description set forth the general arrangements and constructions of the several devices and parts comprising a game-apparatus or amusement device embodying the principles of the present invention, we will now briefly set forth the manner of the operation of the several 105 devices and parts of the same.

After having filled the tank 11 with water to a proper height, by means of a prime mover, the pulley-wheel 22 is set in motion. This will cause the shaft 21 to revolve, thus producing a movement of the link-chain 26 in the direction of the arrows, as indicated in Figure 3 of the drawings. Simultaneously the eccentrically disposed pin 46 and the flexible connection 43 cause the toy-figure or doll 42 to receive a slight reciprocating motion, back and forth, whereby the toy-buoy 48 is correspondingly moved in up and downward directions, so that the doll 42 will appear to be raising and lowering the life-buoy, as will be evident. At the same time, the paddle-wheel 33 is also actuated, the rotary action of said wheel causing a current or circulation of the water toward the said buoy 48, and the dolls 55 deposited 110

in the water, in the manner presently set forth, will float toward the said life-buoy.

The operator now places in the car 30 a number of dolls 55, the number of said dolls

- 5 varying according to the number of players, said dolls being also differently numbered or colored so as to distinguish one from the other, and the said car is placed upon the carrier-rails or tracks 13 of the incline 3, in 10 such a position, that the moving push-log or dog 27 is brought into engagement with the extension 32 of the car 30. The latter is thereupon forced up said incline 3, until it reaches the curve 14, over which the car 15 passes and reaches the plane 4. Immediately, the car, due to gravity, passes down the rails 15, and upon reaching the ends 16 of said rails, plunges into the water contained in the tank 11. As the car sinks to 20 the bottom of the tank, the dolls 55 are displaced from the car-body, and float upon the surface of the water, and due to the current produced by the paddle-wheel 33, float in an irregular manner toward the life-buoy 48.
- 25 The first doll floated beneath said buoy is at once attracted by the magnet, and is withdrawn in suspended relation above the surface of the water, as indicated in Figure 7 of the drawings.
- 30 According to the number or color of the doll thus having been removed from the water, the person who selected this doll is declared the winner.

From the foregoing description, it will 35 be seen, that a simple game-apparatus or amusement device has been produced, which is interesting and which will afford amusement to grown up persons, as well as to children.

40 Of course, we are aware, that our invention is capable of changes in the general arrangements and combinations of the various devices and parts, as well as in the details of the construction of the said parts, without departing from the scope of the present 45 invention as set forth in the foregoing specification and as defined in the clauses of the claims which are appended thereto. Hence, we do not limit our present invention to 50 the exact arrangements and combinations of the various devices and parts as described in the said specification, nor do we confine ourselves to the exact details of the construction of the said parts, as illustrated in the 55 accompanying drawings.

We claim:

1. In a game-apparatus or amusement device, in combination with a tank adapted to contain water, a track located outside of 60 said tank, said track having an end-portion terminating above the level of the water in said tank, and the car adapted to be placed upon said track, and adapted to be plunged from the end-portion of the track into and 65 beneath the surface of the water in said

tank, said car being adapted to receive floatable toy-figures, and means connected with said tank for the withdrawal of a toy-figure from the water in said tank.

2. In a game-apparatus or amusement device, in combination with a tank adapted to contain water, a track located outside of said tank, said track having an end-portion terminating above the level of the water in said tank, and a car adapted to be placed 70 upon said track, and adapted to be plunged from the end-portion of the track into and beneath the surface of the water in said tank, said car being adapted to receive floatable toy-figures, a toy-figure outside of 80 and movable with relation to the tank, means for producing movements of said last-mentioned toy-figure, and a magnetic means of attraction carried by said last-mentioned toy-figure for the capture of one of said 85 floating toy figures.

3. A game-apparatus or amusement device, comprising a pair of inclined planes, a track extending up one of said planes and down the other plane, a tank adapted to 90 contain water adjacent to the end of the descending track, a car adapted to be placed upon said track, said car being adapted to receive floatable toy-figures, means for propelling said car in an upward direction 95 upon one of said inclined planes, said car passing by gravity down the other plane to be plunged into the water in said tank, and means connected with said tank for the withdrawal of a toy-figure from the water in 100 said tank.

4. A game-apparatus or amusement device, comprising a pair of inclined planes, a track extending up one of said planes and down the other plane, a tank adapted to 105 contain water adjacent to the end of the descending track, a car adapted to be placed upon said track, said car being adapted to receive floatable toy-figures, means for propelling said car in an upward direction upon 110 one of said inclined planes, said car passing by gravity down the other plane to be plunged into the water in said tank, and a magnetic means of attraction in the form of a life-buoy connected with said tank for 115 attraction of a toy-figure and withdrawal of the same from the water.

5. A game-apparatus or amusement device, comprising a pair of inclined planes, a track extending up one of said planes and 120 down the other plane, a tank adapted to contain water adjacent to the end of the descending track, a car adapted to be placed upon said track, said car being adapted to receive floatable toy-figures, means for propelling said car in an upward direction upon 125 one of said inclined planes, said car passing by gravity down the other plane to be plunged into the water in said tank, means for agitating the body of water in said tank, and 130

means connected with said tank for the withdrawal of a toy-figure from the water in said tank.

6. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable toy-figures, means for propelling said car in an upward direction upon one of said inclined planes, said car passing by gravity down the other plane to be plunged into the water in said tank, means for agitating the body of water in said tank, and a magnetic means of attraction in the form of a life-buoy connected with said tank for attraction of a toy-figure and withdrawal of the same from the water.

7. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable toy-figures, means for propelling said car in an upward direction upon one of said inclined planes, said car passing by gravity down the other plane to be plunged into the water in said tank, a platform connected with said tank, said platform projecting above the surface of the water, a movable toy-doll mounted upon said platform, and means carried by said toy-doll for withdrawal of a toy-figure from the water in said tank.

8. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable toy-figures, means for propelling said car in an upward direction upon one of said inclined planes, said car passing by gravity down the other plane to be plunged into the water in said tank, a platform connected with said tank, said platform projecting above the surface of the water, a movable toy-doll mounted upon said platform, and a magnetic means of attraction in the form of a life-buoy carried by said toy-doll for withdrawal of a toy-figure from the water in the tank.

9. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable toy-figures, means for pro-

pellng said car in an upward direction upon one of said inclined planes, said car passing by gravity down the other plane to be plunged into the water in said tank, a platform connected with said tank, said platform projecting above the surface of the water, a movable toy-doll mounted upon said platform, means for agitating the body of water in said tank, and means carried by said toy-doll for withdrawal of a toy-figure from the water in said tank.

10. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable toy-figures, means for propelling said car in an upward direction upon one of said inclined planes, said car passing by gravity down the other plane to be plunged into the water in said tank, a platform connected with said tank, said platform projecting above the surface of the water, a movable toy-doll mounted upon said platform, means for agitating the body of water in said tank, and a magnetic means of attraction in the form of a life-buoy carried by said toy-doll for withdrawal of a toy-figure from the water in the tank.

11. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of said inclined planes, said car passing by gravity down the other plane to be plunged into the water in said tank, and means connected with said tank for withdrawal of one of said floatable dolls from the water in said tank.

12. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of said inclined planes, said car passing by gravity down the other plane to be plunged

into the water in said tank, and a magnetic means of attraction in the form of a life-buoy connected with said tank for attraction of one of said floatable dolls from the water 5 in said tank.

13. A game-apparatus or amusement device, comprising a pair of inclined planes, a track extending up one of said planes and down the other plane, a tank adapted to 10 contain water adjacent to the end of the descending track, a car adapted to be placed upon said track, said car being adapted to receive floatable dolls, a pair of sprocket-wheels and a link-chain passing over and 15 about said sprocket-wheels, means for actuating the same, a dog carried by said chain for engagement with the car to push the same in an upward direction upon one of said inclined planes, said car passing by 20 gravity down the other plane to be plunged into the water in said tank, means for agitating the body of the water in said tank, and means connected with said tank for withdrawal of one of said floatable dolls from 25 the water in said tank.

14. A game-apparatus or amusement device, comprising a pair of inclined planes, a track extending up one of said planes and down the other plane, a tank adapted to 30 contain water adjacent to the end of the descending track, a car adapted to be placed upon said track, said car being adapted to receive floatable dolls, a pair of sprocket-wheels and a link-chain passing over and about said 35 sprocket-wheels, means for actuating the same, a dog carried by said chain for engagement with the car to push the same in an upward direction upon one of said inclined planes, said car passing by gravity 40 down the other plane to be plunged into the water in said tank, means for agitating the body of the water in said tank, and a magnetic means of attraction in the form of a life-buoy connected with said tank for attraction of one of said floatable dolls from 45 the water in said tank.

15. A game-apparatus or amusement device, comprising a pair of inclined planes, a track extending up one of said planes and 50 down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of 55 said inclined planes, said car passing by gravity down the other plane to be plunged into the water in said tank, a platform connected with said tank, said platform projecting above the surface of the water, a 60 movable toy-doll mounted upon said plat-

form, and means carried by said last-mentioned toy-doll for withdrawal of a floatable doll from water in said tank.

16. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of said inclined planes, said car passing by gravity down the other plane to be plunged into the water in said tank, a platform connected with said tank, said platform projecting above the surface of the water, a movable toy-doll mounted upon said platform and a magnetic means of attraction in the form of a life-buoy carried by said last-mentioned toy-doll for withdrawal of one 90 of said floatable dolls from the water in the tank.

17. A game-apparatus or amusement device, comprising a pair of inclined planes, a track extending up one of said planes and down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of said inclined planes, said car passing by gravity down the other plane to be plunged into the water in said tank, a platform connected with said tank, said platform projecting above the surface of the water, a movable toy-doll mounted upon said platform, means for agitating the body of water in said tank, and means carried by said last-mentioned toy-doll for withdrawal of a floatable doll from the water in said tank.

18. A game-apparatus or amusement device, comprising a pair of inclined planes, a tank extending up one of said planes and down the other plane, a tank adapted to contain water adjacent to the end of the descending track, a car adapted to be placed upon said track, said car being adapted to receive floatable dolls, a pair of sprocket-wheels and a link-chain passing over and about said sprocket-wheels, means for actuating the same, a dog carried by said chain for engagement with the car to push the same in an upward direction upon one of said inclined planes, said car passing by gravity down the other plane to be plunged 125

- into the water in said tank, a platform connected with said tank, said platform projecting above the surface of the water, a movable toy-doll mounted upon said platform, 5 means for agitating the body of water in said tank, and a magnetic means of attraction in the form of a life-buoy connected with said tank for attraction of one of said floatable dolls from the water in said tank.
- 10 19. In a game-apparatus or amusement device, in combination with a tank adapted to contain water, a platform mounted upon said tank, said platform projecting above the water in said tank, a toy-doll movably mounted upon said platform, means for moving said doll, and a magnetic means of attraction carried by said doll, consisting of a circular envelope provided with a centrally disposed open portion, and a ring-shaped magnet 15 within said envelope, said magnet having a marginal portion extending from said envelope and projecting into said centrally disposed open portion of the envelope.
- 15 20. In a game-apparatus or amusement de-

vice, in combination with a tank adapted to 25 contain water, a shaft, means for revolving said shaft, a pin extending eccentrically from said shaft, a platform mounted upon said tank, said platform extending above the water in said tank, a toy-doll movably 30 mounted upon said platform, a flexible connection between said pin and said doll for actuating the same, and a magnetic means of attraction carried by said doll, consisting of a circular envelope provided with a centrally 35 disposed open portion, and a ring-shaped magnet within said envelope, said magnet having a marginal portion extending from said envelope and projecting into said centrally disposed open portion of the envelope. 40
In testimony, that we claim the invention set forth above we have hereunto set our hand this 6th day of March, 1921.

FRANK A. PFEIFER.
